(57) **CLAIM**

I claim the ornamental design for a jigsaw power tool,
substantially as shown.

DESCRIPTION

FIG. 1 is a perspective view of the jigsaw power tool.

FIG. 2 is an opposite perspective view of the jigsaw power
tool.

FIG. 3 is a side view of the jigsaw power tool.

FIG. 4 is top view of the jigsaw power tool.

FIG. 5 is a bottom view of the jigsaw power tool.

FIG. 6 is a front view of the jigsaw power tool; and,
FIG. 7 is a rear view of the jigsaw power tool.
